CLAIM

The ornamental design for a magnetic identification label, as shown and described.

DESCRIPTION

FIG. 1 is a front perspective view of a magnetic identification label, showing our new design;

FIG. 2 is a top plan view thereof;

FIG. 3 left side elevation view thereof;

FIG. 4 is an end elevation view thereof; and,

FIG. 5 is a front perspective view of a magnetic identification label shown in an environment of use.

The broken line portion of the figure drawings is included to show environment that forms no part of the claimed design.
